UNITED STATES PATENT OFFICE.

RAY W. ARMS, OF CHICAGO, ILLINOIS, ASSIGNOR TO ROBERTS AND SCHAEFER COMPANY, OF CHICAGO, ILLINOIS, A CORPORATION OF ILLINOIS.

DRY SEPARATING APPARATUS.

Application filed April 7, 1924. Serial No. 704,553.

My invention relates to a dry separating apparatus and has for one object to provide means for supplying the air under pressure to a plurality of separating tables from a single pressure or supply source. Another object is to provide an apparatus whereby when a single air pump or fan provides all the air for a plurality of separating tables, temporary change in the air requirements of any table or tables will not seriously affect the operation of the balance of the table and will not seriously affect the pressure available for the supply of air to any table. Another object is to provide a plenum arrangement whereby air can be fed from a single source such as a fan to a plurality of tables and whereby the pressure in the plenum chamber may be automatically held constant independent of operating variations in the air demand and whereby the pressure throughout the entire length of the plenum chamber and therefore the pressure available to supply air to each separating table may be substantially constant. Other objects will appear from time to time in the specification and claims.

My invention is illustrated more or less diagrammatically in the accompanying drawings, wherein—

Figure 1 is a longitudinal section through a plenum chamber showing tables in elevation;

Figure 2 is a plan view.

Like parts are indicated by like characters throughout the specification and drawings. A is a working floor supported by the usual beams and girders not here shown. Resting on this floor are a plurality of separating tables A¹, A¹ arranged as here indicated in two parallel banks of four each, though there might be more or less of these tables, they might be in parallel banks or in a single bank as the case may be. Coal or ore or other material to be separated or classified is fed to these tables through chutes A² A² from any suitable supply source. The operation of these tables forms no part of my present invention. Suffice it to say that the table deck reciprocates and granular material passes across and air passes up through the stream of material across the deck to effect the separation. The material leaves these tables through chutes A³ discharging onto a belt conveyor A⁴ and traveling about an idler pulley A⁵, a driving pulley A⁶ and

discharging through a chute A⁷. Other material leaves the table through chutes A⁸, being carried off by any suitable mechanism not here shown.

Arranged below the floor A is a plenum chamber B. This chamber I have shown as rectangular in cross section though it might be circular or any other shape. This table is larger at the receiving or feed end and tapers downwardly toward the discharge end. Leading from this chamber are a plurality of air pipes B¹, B¹ communicating with flaring chimneys B² B² which in turn discharge against the underside of the separating decks B³ on the separating tables. B⁴ is a fan discharging air through the throat B⁵ to the plenum chamber at its larger end. The wall of the chamber is rapidly expanded as at B⁶ about the discharge end of the throat B⁵ to its maximum cross section before any of the air pipes B¹ are reached and from its largest cross section tapers down as indicated. The angle of inclination of the wall of the plenum chamber together with its size, the size of the airpipes B¹ and the capacity of the fan and the air requirements of the separating decks is preferably so proportioned so as to keep the velocity of the air in the plenum chamber below one thousand feet per minute.

In order that the velocity of the air passing through the chamber and the pressure which forces the air out of it through the chimneys and deck may be maintained substantially constant, it is necessary to provide means for controlling the air input to the chamber and many suitable means might be used for this purpose. I have shown two which may be operated separately or in co-operation as the case may be.

C is an electric motor driving the fan through a belt C¹. Power comes to the motor through the conductors C² and control switch or rheostat C³. Movement of the switch arm C⁴ will change the speed of the motor and therefore the air out-put of the fan. A shutter C⁵ also controls the intake C⁶ of the fan and movement of that shutter will control the air drawn into the fan independent of the motor. I have shown the shutter C⁵ and the switch arm C⁴ both controlled from a pressurestat C⁶ communicating with the interior of the plenum chamber, the pressurestat is connected with levers

C^7 , C^8 which in turn carry linkage C^9 , C^{10} controlling the switch arm C^4 , and the shutter respectively.

One or both of these control devices may be used since in each case they respond to the pressure of the air in the plenum chamber and if a large amount of air is drawn off and the pressure drops, the motor will be speeded up or the intake opened or if less air is used, the opposite action takes place. If the motor control is not used, then it will be necessary to provide within the switch housing some kind of a speed regulation for the motor so that when the shutter C^5 closes and the fan tends to work in an area of lower pressure, the motor will not run away.

I have also shown a bristol gauge type of control as at D communicating with the plenum chamber with electric conductors D^1 leading to and controlling the switch.

It will be evident that while I have shown an operative device, still many changes

might be made in the size, shape and arrangement of parts without departing from the spirit of my invention and I wish therefore that my showing be taken as in a sense diagrammatic. 25

I claim:

The combination with a plurality of independent air separating tables of an air pump and means for operating it, a tapered air chamber extending from the pump adjacent said tables and decreasing in cross sectional area from the pump toward the furthermost chamber and passages placed along the chamber and leading one to each table, automatic means controlled by the pressure of air in the chamber for regulating the amount of air fed by the pump to the chamber. 30 35 40

Signed at Chicago, county of Cook, and State of Illinois, this 20th day of March, 1924.
